Primary Examiner — Susan Bennett Hattan*Assistant Examiner* — Landon Thomas Cassell(74) *Attorney, Agent, or Firm* — Rabin & Berdo, P.C.(57) **CLAIM**

The ornamental design for a bus bar for fuses, as shown and described.

DESCRIPTION

FIG. 1 is a perspective view of a bus bar for fuses;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged top view of the detail identified in FIG. 6; and,

FIG. 9 is an enlarged bottom view of the detail identified in FIG. 7.

The broken lines encircling the areas of enlargement form no part of the claim.
